(57) **CLAIM**

The ornamental design for table-top box for touchscreen and LCD keypad, as shown and described.

DESCRIPTION

FIG. 1 is an elevated perspective view from the right of the table-top box for touchscreen and LCD keypad in accordance with our invention.

FIG. 2 is a front view thereof;

FIG. 3 is a perspective back view thereof;

FIG. 4 is a back view thereof;

FIG. 5 is a side view thereof; and,

FIG. 6 is a top view of our invention as shown in FIG. 1.
